HERBERT FREDERICK HENRY SHIELDS, OF WELLING, AND JOHN PEARCE ROE, OF LONDON, ENGLAND, ASSIGNORS TO ROPEWAYS LIMITED, OF LONDON, ENGLAND.

AERIAL ROPEWAY.

1,347,763.

Specification of Letters Patent. Patented July 27, 1920.

Application filed August 21, 1919. Serial No. 319,012.

To all whom it may concern:

Be it known that we, HERBERT FREDERICK HENRY SHIELDS and JOHN PEARCE ROE, subjects of the King of England, residing at 5 Welling, in the county of Kent, England, and London, England, respectively, have invented certain new and useful Improvements in Aerial Ropeways, of which the following is a specification.

10 This invention relates to aerial ropeways of the kind in which a single rope carries detachable boxheads, and in which the load, supported vertically beneath the rope, is carried by a hanger extending laterally out- 15 side the plane containing the load and the rope. The invention has for its main object to provide means whereby the high trestles which at present are commonly used where the ropeway passes over depressions, may 20 be dispensed with, one or more shorter trestles being substituted therefor; a second object of the invention is to provide means for producing pressure on adjacent supporting sheaves.

25 It will be appreciated that the high trestle becomes necessary because the rope is ordinarily only carried over a supporting sheave which must be at such a height that when the rope is unloaded and is therefore 30 pulled tight under the tensioning means it will not lift from the sheave; when the rope is loaded there is, of course, no tendency for it to lift from the sheave even if the latter were placed lower than the level required 35 for the reason stated.

It has been proposed to provide holding-down means for the rope to avoid the use of high trestles, but difficulties arise owing to the fact that the boxheads or carriers, 40 which are secured to the rope for carrying the loads, have to pass such holding-down means. When the carrier in use is a simple band fixed to the rope it may be allowed to pass as one with the rope between opposed 45 sheaves, that is a depression-sheave and a supporting-sheave vertically beneath it. These carriers, however, are little employed because they make it impossible to run the load from the rope on to shunts. If the 50 detachable form of boxhead is employed which is larger than the simple fixed carrier, the boxhead is either knocked off the rope when it comes into contact with the depression-sheave, or it or both are dam-

aged. To avoid this difficulty and yet use 55 the detachable carrier, it has been proposed to limit the load on the depression-sheave. This, however, means that the rope can only be moderately depressed and therefore the gain effected is inappreciable. With a de- 60 pression-sheave whose load is thus limited, it has also been proposed to use a yieldingly-controlled supporting-sheave placed oppo- 65 site the depression-sheave so that when a load is passing, the rope is carried by the yieldingly-supported sheave. This moving 70 sheave is inclined to get out of order, and, as already stated, the degree of depression possible by this method is but slight.

Further, at places where the gradient of 70 a rope changes it has been proposed to provide a depression-sheave between two supporting-sheaves mounted at different levels 75 on a trestle carrying a short shunting rail at the side of the sheaves, but these sheaves were not spaced apart as described herein- 80 after, nor did the boxhead pass under the depression-sheave.

An aerial ropeway of the kind described according to this invention comprises the 80 combination with a depression-sheave, of guides constructed to engage by their under faces a boxhead as the rope carries it past the sheave, the undersides of which guides rise with an easy incline from their ends 85 adjacent to the sheave to their outer ends, which guides moreover extend on either side of the sheave to points spaced considerably farther apart than are the opposite ends of any one boxhead passing beneath them. 90 Preferably the guide is so shaped in cross- 95 section on its under side as to guide the rope on to the sheaves should it at any time tend to be displaced laterally therefrom.

Another object is to provide a boxhead of 95 an improved construction for an aerial rope- 100 way of the kind described. Where the box- head is provided with off-set side wheels on one side of it for shunting purposes accord- 105 ing to this invention, an off-set steadyng- piece (for example another pair of off-set wheels) may be provided on the opposite side of the boxhead, the wheels and steadyng- piece being made both to so engage the guide as to keep the boxhead at the same angle laterally when passing a guide as it assumes when free of the same. This ar- 110 rangement prevents the setting up of a lat-

eral swing on the load when engaging the guide, and if double shunting rails are employed, placed at the proper level relatively to one another, the same wheels and steady-
5 ing-piece will prevent lateral swing being set up when the load is transferred to or delivered from such shunting rails.

Another important object of this invention is to provide a boxhead-guide of the 10 kind referred to above so arranged that the deflection of the rope from its normal position caused by a boxhead passing between a depression-sheave and the rope shall be less than that which occurs when the guide 15 is normally fixed on the trestle.

Another object is to enable a boxhead provided with only one set of off-set wheels on one side thereof to be used with guides of the kind described applied to depression- 20 sheaves, whereby an additional set of off-set wheels on each boxhead is avoided.

A further object is to provide the boxhead-guide for use with a boxhead as just described with an anti-friction device for reducing the friction between the guide and a non-rotatable steadyng-piece on the side of the boxhead remote from that provided with off-set wheels.

A still further object is to provide that 30 a boxhead-guide shall adjust itself automatically to any inclination or angle of the rope.

Other features of the invention are described hereinafter and pointed out in the 35 claims.

The invention is illustrated by way of example in the accompanying drawings, wherein:—

Figure 1 is a side elevation showing a depression-sheave provided with one form of guide according to the invention, and an improved boxhead passing under the same, part of the guide being broken away, and

Fig. 2 is an end elevation thereof, partly 45 in section through the center of the guide for the boxhead;

Fig. 3 is a diagrammatic side elevation, showing part of an aerial ropeway constructed according to the invention;

Fig. 4 is a side elevation showing a modified form of boxhead-guide according to the invention, a boxhead being shown situated in a middle position relatively thereto;

Fig. 5 is a like view, enlarged, of the 55 modified guide as seen from the other side, showing only one end of the guide with the boxhead vertically under a depression-sheave in that end;

Fig. 6 is a vertical section taken on the 60 line 6—6 in Fig. 5, partly in elevation;

Fig. 7 is a side elevation showing one form of a modified construction of anti-friction device provided on a boxhead-guide according to the invention, and

Fig. 8 and 9 are detail views, enlarged,

showing in vertical section and side elevation, respectively, the anti-friction device shown in Fig. 7.

Like reference letters designate like parts throughout the several views. 70

Referring first to Figs. 1 to 3 the rope-way comprises an endless moving hauling cable or rope A which is guided on a number of trestles B¹ to B⁷ by supporting-sheaves C and depression-sheaves D mounted on the 75 trestles. Each depression-sheave D is provided with a guide E for guiding the rope and boxheads F carried by the latter. A bucket G is suspended from each boxhead in the usual manner. As shown in guide E 80 Figs. 1 and 2, the boxhead F is provided with two off-set wheels F¹ on one side of it for shunting purposes in the usual manner, and is arranged to be secured to the rope A by detachable clips or jaws F² such as are 85 already well-known, but the boxhead is further provided with a second pair of off-set wheels F³ disposed on the opposite side to that whereon the first set is mounted.

Each depression-sheave D is mounted to 90 rotate vertically above the rope A in its guide E which extends forwardly and rearwardly of the same. This guide E is built up of two plates E¹, E² placed side by side, bolted together and hung by pins E³ from the cross-beams B of the trestle. Each plate E¹, E² has at its lower edge an outwardly directed flange E⁴, E⁵ respectively, which is curved in cross-section so that the two flanges provide an approximately concave face on 95 the under side. The working portion of the grooved rim of the pulley D lies in the center of this concave face and at a point approximately midway between the ends of the channel thus provided, and the whole channel is made convex or cam-shaped in the direction of travel, that is to say, a horizontal straight line joining the ends of the guide lies higher than the center of it. The length 100 of the guide E is such that its opposite ends are considerably farther apart than are the opposite ends of any one boxhead passing beneath it. The off-set wheels F¹ and F³ of the boxhead are so spaced apart that as the boxhead arrives at the guide E the 105 wheels will enter the channel therein, and by bearing against the one end of the guide the boxhead will be smoothly forced down to the sheave and delivered with equal smoothness therefrom by the other end of 110 the guide.

The trestles shown in Fig. 3 are erected at the bottom of a wide valley. A trestle B⁴ having a single depression-sheave D with its guide E is provided in the middle 115 of the spanned dip, and other trestles B⁵, B⁶ are disposed, one on the receiving and the other on the delivery side of the same, each carrying a supporting sheave C. Other trestles B², B⁷ each having a depression- 120

130

sheave D are erected on either side of these trestles B³ to B⁵, and still other trestles B¹ B⁷, each carrying two supporting sheaves, are erected beyond the former trestles. The 5 distance between the supporting sheaves and the adjacent depression-sheaves is such that when a boxhead passes a depression-sheave with a load which is in excess of a predetermined minimum it shall cause the ropeway 10 to sag sufficiently to clear the depression-sheave and its guide without touching the same.

It will be seen that so long as a ropeway having its parts constructed as described 15 above is carrying loads which are in excess of a predetermined minimum the boxheads will not be subjected to any shock in passing the depression-sheave, as owing to the sag of the rope the engaging wheels will be too 20 low to come into contact with their guide, but as soon as the boxhead has passed the depression-sheave the rope itself returns into the groove in the sheave either directly or with the aid of the guide, and so will 25 always be kept in place. If the loads carried by the ropeway are lighter than the predetermined minimum, then each boxhead will engage the guide of the depression-sheave and so force the rope down to allow 30 the boxhead to pass, but the shock will be less than would be the case if a heavier load were being carried without provision for sag, and the displacement will be easily effected because it is brought about gradually 35 by the inclined face of the guide.

As the axes of the off-set wheels are set at right angles to the line of suspension of the load, it will be appreciated that there is no tendency to set up a lateral swing as 40 the load passes a depression-sheave, whereas this would be the case if wheels were used on only one side of the boxhead and no steadyng-device were provided on the other. Similarly, when the load is being 45 shunted from the ropeway by using two shunt rails instead of one and engaging both pairs of wheels with the rails, the line of suspension can again be maintained the same on the shunt rails as on the ropeway. 50 Owing to the transverse wheel-base of the boxhead being relatively large greater safety is afforded to the passing boxhead.

Obviously it is not necessary to use two pairs of wheels as a single wheel would 55 do on one side, or even a guiding pin. Also a boxhead F⁴ (Fig. 3) having only one pair of off-set wheels F¹ and no guide on the other side can be used, but in this case the force tending to swing the boxhead and the bucket carried thereby about the rope must be taken up by a guard or abutment B⁸, carried by the trestle, as indicated in dotted lines in Fig. 2. Further, it is clear that 60 fixed clips of the known form can be used 65 consisting of a thin steel band placed around

the rope and then tightened. The empty bucket G is shown in dotted lines as suspended from such a fixed clip H.

Referring now to Figs. 4-6, a boxhead or carrier F⁰, which is provided with two off-set wheels F¹ on one side of it for shunting purposes in the usual manner, is further provided with a non-rotatable off-set steadyng-piece in the form of an inverted slipper F⁶ constituted by a curved flange formed 70 on the frame of the boxhead and extending from end to end thereof.

A boxhead-guide J for guiding boxheads or carriers F⁰ past depression-sheaves D¹, D² has the form of a double-ended lever or 80 beam which comprises plates J¹, J² bolted together and is fulcrumed to rock about a pivot-pin K secured to a cross-beam B of a trestle. Two depression-sheaves D¹, D² are mounted on the rocking guide J, the 85 distance apart of the sheaves being such that they normally depress the rope A at two points spaced considerably farther apart than are the opposite ends of any one boxhead passing beneath them. Allotted 90 to each of the depression-sheaves and situated at one side thereof are curved guide rails J³ which are for guiding the wheels F¹ of a boxhead passing under the guide J, and on the opposite side are provided curved 95 guide rails J⁴, for guiding the slippers F⁶ of the boxheads. Each rail J⁴ has allotted to it two sprocket-wheels M and M¹ mounted between the plates J¹, J² and carrying a roller chain N which constitutes an anti-friction device for co-acting with the steadyng-pieces. 100

It will be seen that by providing a recess at J⁵ in the middle portion of the guide J the operative faces of the guide are divided 105 into two parts, one for each depression-sheave. The depth of this recess is greater than the height of any one boxhead passing beneath the guide, and the inner ends of the guides rise gently into the recess. Owing 110 to the guide members being curved as shown, the rope leaves and returns to the depression-sheaves gradually when the boxheads enter under and leave a depression-sheave, whereby undue shocks on the boxheads are 115 avoided.

Referring to Figs. 7 to 9, the curved guide rail J⁴ instead of being provided with a roller chain N as described above, has a series of staggered anti-friction rollers O, 120 O¹ mounted thereon which are arranged to co-act with the slipper F⁶ of a boxhead passing beneath them.

It will be appreciated that instead of the lower part of a boxhead-guide being curved 125 in cross-section and having an approximately concave face on its underside, as described above with reference to Figs. 1 and 2, for accommodating two sets of off-set wheels on a boxhead, a guide comprising a 130

rail, such as J^3 , on one side for co-acting with wheels on only one side of a boxhead may advantageously be employed in conjunction with a roller chain, such as N , and with staggered rollers such as O , O^1 arranged on the other side of the guide and adapted to co-act with a part, such as the slipper F^6 , fixed on the frame of a boxhead. Such an arrangement enables boxheads having each only one set of off-set wheels to be employed with a guide that is not mounted to rock on the trestle carrying it.

The employment of a pivotally mounted guide, such as J , has the advantage that it will automatically adjust itself to any inclination or angle of a rope, and, further, it can be mounted upon the usual gudgeon provided for the reception of ordinary mounts when a series of compensating sheaves are employed. Again, when a boxhead is passing one depression-sheave in a rocking guide and temporarily presses the rope away from that sheave; the rope remains in the groove of the second sheave 25 in the same guide and is always depressed by either one or both depression-sheaves.

It is to be understood that the details of construction of the guides, whether fixed or movable, described above for the depression-sheaves may be varied, and also the construction of the boxheads, without departing from the scope of the invention as defined in the claims. For example, the guide E or J instead of comprising plates bolted together 35 can be made in one piece with a slot for accommodating the depression-sheave. Further, instead of a guide having arms of equal length, the one depression-sheave may be pivotally mounted farther from its fulcrum-piece than is the other, and in lieu of anti-friction roller-chains or the like plane rope guides may be employed. Moreover, the lay-out of the ropeway will vary according to the conditions in each case, and according 40 to the type of boxhead or carrier it is proposed to employ.

What we claim as our invention and desire to secure by Letters Patent is:-

1. A device of the character described for coöperation with boxheads of aerial ropeways, comprising a depression-sheave, and guides on opposite sides thereof, said guides having a length greater than the length of a single boxhead, substantially as described.

55 2. A device of the character described for coöperation with boxheads of aerial ropeways, comprising a depression-sheave, and guides on opposite sides thereof having their lower surfaces inclined downwardly toward the sheave, said guides also having a length greater than the length of a single boxhead, substantially as described.

60 3. A device of the character described for coöperation with boxheads of aerial ropeways, comprising a depression-sheave, and

guides on opposite sides thereof, said guides having their lower surfaces gradually inclined downwardly toward the sheave and having a length greater than the length of a single boxhead, substantially as described. 70

4. A device of the character described, comprising a depression-sheave, and guides on opposite sides thereof, said guides having their lower surfaces inclined downwardly toward the sheave, substantially as described. 75

5. A device of the character described, comprising a depression-sheave, and guides on opposite sides thereof, said guides having their lower surfaces inclined downwardly and inwardly toward the sheave, substantially as described. 80

6. In an aerial ropeway of the character described, comprising a depression-sheave, a boxhead, offset side wheels on one side of the boxhead for engagement with the usual shunting rails, and an offset steadyng-piece on the opposite side of the boxhead, substantially as described. 85

7. The combination in an aerial ropeway of the character described, comprising a depression-sheave, of a boxhead having offset side wheels on both sides thereof for engagement with the usual shunting rails, and guides for engagement with said wheels, substantially as described. 90

8. In an aerial ropeway of the character described, comprising a depression-sheave, a boxhead, offset side wheels on one side of the boxhead for engagement with the usual shunting rails, an offset steadyng-piece on the opposite side of the boxhead, and guides cooperating with said wheels and steadyng-piece, substantially as described. 100

9. In an aerial ropeway of the character described, comprising a depression-sheave, a boxhead having a shunting wheel on each side thereof, and guides having inclined surfaces coöperating with said wheels, substantially as described. 105

10. In an aerial ropeway of the character described, the combination with a hauling cable, of spaced supporting sheaves therefor, a depression-sheave intermediate said supporting sheaves and a boxhead adapted to be moved by the cable beneath said supporting sheave, the weight of the load carried by said boxhead determining the engagement between the depression-sheave and the boxhead, substantially as described. 115

11. In an aerial ropeway of the character described, the combination with a hauling cable, of a plurality of supporting sheaves engaging said cable at different points, a depression-sheave intermediate adjacent supporting sheaves and normally in engagement with said cable, and a load-carrying boxhead on said cable adapted to draw the cable out of engagement with the depres- 120
125
130

- sion-sheave with any load in excess of a pre-determined minimum, substantially as described.
12. A boxhead guide of the character described, comprising a pivoted guide member, depression-sheaves carried thereby and journaled in the guide, and a hauling cable in engagement with said sheaves, substantially as described.
- 10 13. A boxhead guide of the character described, comprising a guide, a fulcrum therefor, and depression-sheaves journaled in the guide, substantially as described.
14. A boxhead guide of the character described, comprising a guide, a fulcrum therefor, and depression-sheaves journaled in the guide on opposite sides of the fulcrum, said guide having its lower edge inclined for cooperation with a boxhead, substantially as described.
- 15 16. A boxhead guide of the character described, comprising a guide, a fulcrum therefor, and depression-sheaves journaled in the guide on opposite sides of the fulcrum, said 25 guide having its lower edges provided with anti-friction means for engaging with a boxhead, substantially as described.
- 20 17. A boxhead of the character described, comprising spaced guides, a fulcrum therefor, depression-sheaves intermediate said 30 guides, and journals for said sheaves on opposite sides of said fulcrum, substantially as described.
- 35 18. A boxhead of the character described, comprising spaced guides, a fulcrum therefor, depression-sheaves intermediate said 40 guides, and journals for said sheaves on opposite sides of said fulcrum, said guides having their lower edges formed for engagement with a boxhead, substantially as described.
- 45 19. A device of the character described for use with boxheads having offset side wheels on one side only, comprising a guide 50 for engagement with said wheels, and a second guide for engagement with the opposite side of the boxhead, substantially as described.
- 55 20. A boxhead guide according to preceding claiming clause No. 19, wherein the anti-friction devices are in the form of endless chains, substantially as described. 60
21. A boxhead guide of the character described, comprising a guide member having a recess of a depth greater than the height of a boxhead, said member having guide faces on opposite sides of said recess for engagement with a boxhead, and a fulcrum for said mounting, substantially as described. 65
22. A boxhead guide of the character described, comprising a guide member having a recess of a depth greater than the height of a boxhead, said member having guide faces on opposite sides of said recess for engagement with a boxhead, a fulcrum for said member, and depression-sheaves carried by said member on opposite sides of said 70 fulcrum, substantially as described.
23. The combination in an aerial ropeway of double shunting rails, and a boxhead having a plurality of offset side wheels for engagement with said rails, substantially as 75 described. 80
24. The combination in an aerial ropeway of a plurality of double shunting rails and a boxhead having an offset side wheel at each side thereof for engagement with said rails, substantially as described. 85

In testimony whereof we have signed our names to this specification.

HERBERT FREDERICK HENRY SHIELDS.

JOHN PEARCE ROE.
